UNITED STATES PATENT OFFICE.

CHARLES CHAMBELLAN, OF NEW YORK, N. Y., ASSIGNOR TO THE BIGELOW CARPET COMPANY, OF CLINTON, MASS.

DESIGN FOR CARPETS.

SPECIFICATION forming part of Design No. 12,190, dated March 22, 1881.

Application filed February 16, 1881. Term of patent 3½ years.

To all whom it may concern:

Be it known that I, CHARLES CHAMBELLAN, of the city of New York, county and State of New York, have invented a new and original 5 Design for Carpets, of which the following is a specification.

This invention relates to a new and original design for carpets and similar fabrics; and it consists in the novel grouping and configuration of figures, hereinafter more fully described.

The accompanying photograph illustrates a face view of a carpet having my new design.

A is a figure composed of flowers resembling roses, somewhat scattered, and more or less open, with leaves and moss-like sprays between them, and having a projecting branch, e, bearing leaves and rose-buds.

D is a bouquet composed of rose-like flowers 20 surrounded by leaves and vines.

C is a figure composed of a rose, rose-buds, and circular flowers with accompanying leaves.

B is a figure having a daisy-like flower for its center, surrounded by leaves, and with 25 roses projecting around the center.

The figures b a h g d represent different portions of the ornamented background, some-

what resembling fence-work or trellis-work, and filling the interstices between the figures described.

The effect of the design is that produced by the various figures described, placed at regular intervals and connected by the trellis-like figure forming the background.

I claim—

- 30 1. The design for carpets, consisting of the figure A, substantially as shown.
2. The design for carpets, consisting of the figure B, substantially as shown.
